UNITED STATES PATENT OFFICE.

ROLF THELEN, OF MADISON, WISCONSIN, DEDICATED, BY MESNE ASSIGNMENTS, TO
THE CITIZENS OF THE UNITED STATES OF AMERICA

REVERSIBLE CIRCULATION INTERNAL FAN KILN.

Application filed May 18, 1923. Serial No. 640,280.

(FILED UNDER THE ACT OF MARCH 3, 1883, 22 STAT. L. 625.)

To all whom it may concern:

Be it known that I, ROLF THELEN, a citizen of the United States of America, and an employee of the Department of Agriculture, residing in Madison, Wisconsin, (whose post-office address is Madison, Wisconsin,) have invented a new and Improved Reversible Circulation Internal Fan Kiln.

This application is made under the act 10 of March 3, 1883, Chapter 143 (22 Stat. 625), and the invention herein described and claimed may be used by the Government of the United States, its officers and employees, and by any person in the United States 15 without the payment to me of any royalty thereon. I hereby dedicate the same to the free use of the Government and the people of the United States.

My invention consists in an improvement 20 in the design of forced circulation kilns or chambers for drying and conditioning lumber or similar material. However, its use is not limited to wood or wood products. It consists in the adaptation of fans of the 25 disk type, or similar types, to the production of a unique internal circulation of air and the vapor in the kiln combined with the production and regulation of the heat and the humidity within the kiln.

30 This invention is illustrated in Figures 1 to 3. Figure 1 represents a cross-sectional elevation. Figure 2 represents a horizontal cross-section of the kiln taken directly beneath the track support. Figure 3 represents a vertical longitudinal cross-section near the center of the kiln and shows in detail some of the air distributing system.

The principal feature which I claim as 40 novel and an improvement over existing kilns is the use and arrangement of the fans and the air distributing system. This arrangement is such that a very fast and uniform circulation of air and vapor through the pile of lumber may be secured and permits the periodic reversal of the direction of 45 the air movement by simply reversing the direction of rotation of the fans. The air distributing system provides a very uniform flow of air throughout the length of the kiln and eliminates the non-uniformity 50 of drying, which is one of the commonest troubles experienced in the ordinary kiln.

The arrangement of the fans upon a single shaft extending throughout the length of the kiln provides a simple means of producing a brisk circulation; and the elimination of comparatively small ducts such as those used in external blower kilns reduces very materially the work required to produce a given circulation. The differences in 55 air pressure required in the operation of this kiln are much smaller than those ordinarily required in kilns employing centrifugal blowers, and the disk fans operate very efficiently at these low pressures. It is possible, therefore, by the use of this invention to produce a very great and uniform circulation of air and vapor within the kiln with 60 a very small expenditure of power.

While it is obvious that there are many 70 possible ways in which the use of internal fans can be adapted to drying kilns of different types, this invention is limited to kilns in which the lumber is flat end piled and in which a single row of fans is employed.

Any well-known means of heating the air and the vapor in the kiln may be used in conjunction with this invention. When steam pipes are used they may be arranged 80 beneath the lumber piles or in any other convenient manner. Any convenient form and arrangement of heaters may be used.

The drawings show and the specification describes steam jet pipes for increasing the 85 humidity, and air inlet flues with suitable dampers for decreasing the humidity.

While the drawings show and the specification describes specific means for heating the air and the vapor in the kiln and for 90 regulating the humidity of the air in the kiln, this invention is not limited specifically to the arrangements described, but may make use of any other suitable and well-known means for accomplishing the 95 same purposes. While the drawings illustrate and the specification describes a specific form of flat end piled lumber, the invention is not limited to this particular form since it is equally applicable to all 100 other forms of flat end piling, such as single piles with parallel-sided central chimney and double piling with or without chimneys in each pile. It is also adapted to in-

clined piling in which the layers of lumber are inclined slightly from the horizontal to assist the air movement.

Referring to Figures 1, 2, and 3, which are correspondingly lettered: AA represent the side deflecting partitions. These partitions serve to form a passageway for the air from the heating coils to the fans when the air circulation is in the direction indicated on Figure 1, and when the direction of the air circulation is in the opposite direction they serve to deflect the air delivered by the fans toward the sides and over the heating coils. BB are the fans producing the circulation. Straight-bladed disk fans are preferable. Any type of fan, however, in which the reversal of the direction of rotation of the fan produces a reversal in the direction of flow of the air current passing through the fan can be used. C is the shaft upon which the fans are mounted. Provision is made to take care of the expansion and contraction of this shaft with changes in the temperature in the kiln. DD are air inlet dampers used to regulate and control the amount of air entering the kiln from the outside. EE are the heating coils. The coils illustrated in the drawings and described in the specification are of the return bend type. This invention is, however, not limited to this type since any common or well-known type may be adapted to it. FF are the steam jet pipes used to increase the humidity of the air in the kiln. The lower pair is used when the circulation of air and vapor is downward through the central chimney V and the upper pair is used when the circulation is in the reverse direction. G is the lumber-supporting truck. HH are the shaft hangers. II are bearings for the shaft C. JJ are the tracks upon which the lumber-supporting truck runs. The invention is not specifically limited to the form and arrangement of lumber-supporting truck, tracks, and track support illustrated since any well-known method of supporting the lumber may be used without influencing in any way the efficiency or operation of the kiln. KK are the side walls of the kiln. LL is the lumber to be dried. M is the track support. N is the shaft pulley. OO are air outlet dampers for controlling the amount of air being exhausted from the kiln. P is a belt passing over the pulleys N and Q. Q is the motor pulley. R is the motor which furnishes the power to drive the fans. S is a switch for controlling the speed and rotation of the motor armature. While the drawings show and the specification describes an electric motor, any other suitable driving means may be used. TT are air inlet flues in which the dampers DD are fitted. V is the central chimney in the lumber pile. While the drawings show and the specification describes an upwardly restricted chimney,

chimneys of other shapes, such, for instance, as chimneys with parallel sides may be used. WW are the side air passages which may likewise be of any well-known form as well as of the form illustrated in the drawings and described in the specification. X is the main air distributor. YY are the upper diffusers and ZZ the lower diffusers. The side deflecting partitions, the main air distributor, and the two sets of diffusers form a single air deflecting and distributing unit.

The operation of the kiln is briefly as follows: The lumber is placed in the kiln, the doors and all of the dampers are closed, and the kiln is started. Steam is turned into the coils and one set of steam jets is turned on. Suitable regulating devices are provided to control and regulate the supply of steam to the heating coils and the supply of steam to the steam jets. If it is found impossible to reduce the humidity to the desired point with the steam jets all turned off, the dampers DD and OO are opened to allow fresh air to enter and moist air to escape. These dampers are adjusted so that a humidity below that desired will be secured. The steam jets may then automatically supply a sufficient amount of steam to bring the humidity up to the desired point. If the direction of rotation of the motor, the shaft, and the fans is such that the air and vapor pass upward through the central chimney V, the air and vapor will pass laterally outward through the lumber into the side passages WW, downward through these passages across the heating coils, past the side deflecting partitions, through the fans into the main air distributor which acts as a plenum chamber, a slight pressure being maintained through the action of the fans and the resistance of the upper and lower diffusers. The air then passes from the main air distributor through the lower diffuser Z. The resistance of the upper diffuser Y serves to maintain a slight plenum between the upper and lower diffusers. The air then passes upward through the upper diffuser and into the central chimney, repeating the cycle continuously. The use of the two sets of diffusers in the manner indicated produces a very uniform flow of air throughout the length of the kiln. The unbalancing effect of the horizontal air flow produced by the fans is practically eliminated by allowing a slight pressure to build up in the main distributor. This is still further eliminated by the slight plenum in the space between the upper and lower distributors. It is obvious that the kiln would work reasonably well with a single set of diffusers and that still further uniformity in air distribution might be secured by adding a third or even a fourth set of diffusers. The principle, of course, remains the same and the practical

expediency will determine the balance between increased uniformity of air distribution secured by the addition of more sets of distributors and the loss in efficiency which they cause. It is also obvious that any well-known form of distributor may be used. The invention is not restricted to the form illustrated in which the openings consist simply of spaces between slats running the full length of the kiln. There may, for instance, be a number of openings of circular form, and some or all of these openings may be dampered to permit of individual adjustment of the conditions in each plenum chamber.

It is well understood that when the circulation of the air in the kiln is continuously in one direction, that portion of the pile at which the air enters will dry more rapidly than the opposite side since the air in its passage through the lumber picks up moisture and thus reduces its drying capacity. To overcome this defect, the direction of rotation of the fans may be reversed, thus reversing the direction of the motion of the air through the lumber piles. This may be done periodically every two or three days or oftener, the exact period being determined by the condition of the lumber in the kiln. The direction of the air travel is then as follows: Leaving the fans, the air strikes the side deflecting partitions which deflect it outward against the heating coils; passing through the heating coils, the air travels upward through the side air passages, inward through the lumber, through the central chimney, downward through the central chimney through the upper diffusers and the lower diffusers, into the main air distributor, and thence back to the fans. When the air travels in this direction the heating coils serve to act as distributors, and by the time the air leaves the upper steam jet lines it has become distributed with sufficient uniformity.

Having fully described the principles of this invention and the manner in which they can be embodied in a dry kiln, I claim as original:

1. In a dry kiln arranged for flatwise end piling: a series of fans; a shaft on which the fans are mounted for rotation; means for rotating said shaft in either direction to cause reversal of the circulation of the air and vapor in said kiln; and an air distributing system comprising side deflecting partitions, a main air distributor, and two sets of diffusers.

2. In a dry kiln arranged for flatwise end piling: a series of fans; a shaft on which the fans are mounted for rotation; means for rotating said shaft in either direction to cause reversal of the circulation of the air and vapor in said kiln; dampered air inlet flues and dampered air outlet flues; and an

air distributing system comprising side deflecting partitions, a main air distributor, and two sets of diffusers.

3. In a dry kiln arranged for flatwise end piling: a series of fans; a shaft on which the fans are mounted for rotation; means for rotating said shaft in either direction to cause reversal of the circulation of the air and vapor in said kiln; dampered air inlet flues and dampered air outlet flues; means for heating the kiln and its contents; and an air distributing system comprising side deflecting partitions, a main air distributor, and two sets of diffusers.

4. In a dry kiln arranged for flatwise end piling: a series of fans; a shaft on which the fans are mounted for rotation; means for rotating said shaft in either direction to cause reversal of the circulation of the air and vapor in said kiln; dampered air inlet flues and dampered air outlet flues; means for heating the kiln and its contents; means for humidifying the atmosphere in the kiln; and an air distributing system comprising side deflecting partitions, a main air distributor, and two sets of diffusers.

5. In a dry kiln arranged for flatwise end piling: a series of fans; a shaft on which the fans are mounted for rotation; means for rotating said shaft in either direction to cause reversal of the circulation of the air and vapor in said kiln; a plenum chamber for each fan; and a diffuser with restricted discharge passages for each plenum chamber.

6. In a dry kiln arranged for flatwise end piling: a series of fans; a shaft on which the fans are mounted for rotation; means for rotating said shaft in either direction to cause reversal of the circulation of the air and vapor in said kiln; dampered air inlet flues and dampered air outlet flues; a plenum chamber for each fan; and a diffuser with restricted discharge passages for each plenum chamber.

7. In a dry kiln arranged for flatwise end piling: a series of fans; a shaft on which the fans are mounted for rotation; means for rotating said shaft in either direction to cause reversal of the circulation of the air and vapor in said kiln; dampered air inlet flues and dampered air outlet flues; means for heating the kiln and its contents; a plenum chamber for each fan; and a diffuser with restricted discharge passages for each plenum chamber.

8. In a dry kiln arranged for flatwise end piling: a series of fans; a shaft on which the fans are mounted for rotation; means for rotating said shaft in either direction to cause reversal of the circulation of the air and vapor in said kiln; dampered air inlet flues and dampered air outlet flues; means for heating the kiln and its contents; means for humidifying the atmosphere in the kiln;

a plenum chamber for each fan; and a diffuser with restricted discharge passages for each plenum chamber.

9. In a dry kiln arranged for flatwise end piling: a series of fans; a shaft on which the fans are mounted for rotation; means for rotating said shaft in either direction to cause reversal of the circulation of the air and vapor in said kiln; a series of plenum chambers for each fan; and a diffuser with restricted discharge passages for each plenum chamber.

10. In a dry kiln arranged for flatwise end piling: a series of fans; a shaft on which the fans are mounted for rotation; means for rotating said shaft in either direction to cause reversal of the circulation of the air and vapor in said kiln; dampered air inlet flues and dampered air outlet flues; a series of plenum chambers for each fan; and a diffuser with restricted discharge passages for each plenum chamber.

11. In a dry kiln arranged for flatwise end piling: a series of fans; a shaft on which the fans are mounted for rotation; means for rotating said shaft in either direction to cause reversal of the circulation of the air and vapor in said kiln; dampered air inlet flues and dampered air outlet flues; a series of plenum chambers for each fan; and a diffuser with restricted discharge passages for each plenum chamber.

flues and dampered air outlet flues; means for heating the kiln and its contents; a series of plenum chambers for each fan; and a diffuser with restricted discharge passages for each plenum chamber.

12. In a dry kiln arranged for flatwise end piling: a series of fans; a shaft on which the fans are mounted for rotation; means for rotating said shaft in either direction to cause reversal of the circulation of the air and vapor in said kiln; dampered air inlet flues and dampered air outlet flues; means for heating the kiln and its contents; means for humidifying the atmosphere in the kiln; a series of plenum chambers for each fan; and a diffuser with restricted discharge passages for each plenum chamber.

13. In an internal fan dry kiln adapted for flat end piling: a plenum chamber for each fan; and a diffuser with restricted discharge passages for each plenum chamber.

14. In an internal fan dry kiln adapted for flat end piling: a series of plenum chambers for each fan; and a diffuser with restricted discharge passages for each plenum chamber.

ROLF THELEN.
